John Rogers, of New York, N.Y.
Letters Patent No. 1,135, Dated, April 19, 1876
Design for a . . . figure.

The schedule referred to in these Letters Patent and markings part of the same.

To all whom it may concern:

Be it known that I, John Rogers, of the City of New York, and County and State of New York, have invented or produced a new and original design for a figure; and do hereby declare that the following is a full and exact description of the same.

The design is called 'Mail Day,' and represents a soldier seated on his knapsack, attempting to write a letter. He holds a board on his right knee on which he rests his elbow and strokes his chin with his right hand while he looks up studying for an idea - all of which are clearly seen in the accompanying drawings.

What I claim as my invention or production, and desire to secure by Letters Patent is

The design for a . . . figure as shown and described.
